UNITED STATES PATENT OFFICE.

EDWARD P. CALDWELL, OF MINNEAPOLIS, MINNESOTA.

SNOW-PLOW.

SPECIFICATION forming part of Letters Patent No. 394,244, dated December 11, 1888.

Application filed March 19, 1888. Serial No. 267,684. (No model.)

To all whom it may concern:

Be it known that I, EDWARD P. CALDWELL, of Minneapolis, in the county of Hennepin and State of Minnesota, have invented certain Improvements in Snow-Plows, of which the following is a specification.

The object of my invention is to provide a machine for clearing the snow from railroad-tracks; and I seek to provide a machine by means of which the track may be cleared from any depth of snow.

The invention consists, generally, in a plow consisting, essentially, of a hollow cone-shaped cutter formed of a series of knives arranged with open spaces between them, through which, as the cutter revolves, the snow enters the interior of the cutter and passes out at the rear thereof, from which point it is taken up and thrown outside the track by suitable elevators.

The invention consists, further, in the construction and combination hereinafter described, and pointed out in the claims.

In the drawings forming a part of this specification, Figure 1 is a sectional elevation of a snow-plow embodying my invention. Fig. 2 is a front elevation of the same. Fig. 3 is a front elevation of the cutter, showing a modified arrangement of the knives.

In the drawings, 2 represents a portion of a suitable car, upon which may be supported both the snow-plow itself and the means for driving it. Mounted in suitable standards, 3, upon this car is a longitudinal shaft, 5, that projects for a suitable distance beyond the forward end of the car. This shaft may be driven by any suitable means, but preferably from an engine arranged upon the car 2. Secured to the forward end of the shaft 5 is a conical cutter, formed, preferably, of a series of knives having their cutting portions arranged at an angle to the surface of the cone, and having open spaces between them, through which the snow may pass to the interior of the cutter. Spiders 9 are preferably arranged upon the shaft 5 at suitable distances apart, and a block, 11, is arranged at its forward end, and to these spiders and to this block the knives 7 are preferably secured. In

the rear of the conical cutter I prefer to arrange suitable elevators for taking up the

snow after it has passed through the spaces between the knives and to the rear of the cutter, and carrying it up and throwing it out at the side of the track. Any suitable means 55 may be used for thus removing the snow, such as a conveyer, an exhaust-fan, or an elevator. I have shown in the drawings two elevators, one arranged at each side of the machine. These elevators each consist of a belt, 13, 60 preferably formed of rubber, passing around suitable rolls at the top and bottom of the machine. A series of buckets or slats, 15, are secured upon this belt. The elevators may be driven by a sprocket-chain, 17, from the shaft 65 5. The snow, as it falls into the space behind the conical cutter, is taken up by these elevators, carried upward and dumped on both sides of the track. A suitable apron, 19, is preferably arranged at the bottom and sides 70 of the conical cutter, as shown in Figs. 1 and 2. The apron is provided with a cutting-edge at the bottom, and may be at the sides. The knives 7 may be straight, as shown in Figs. 1 and 2, or they may be of spiral form, as shown 75 in Fig. 3. The conical form of the cutter permits it to be pushed easily into the snow, and but a small amount of power will be required to force the snow-plow through a drift of any size. The cutter being pushed into the snow 80 is rapidly rotated as it is advanced, and the snow is forced in through the open spaces between the knives into the interior of the cutter and passes to its rear end, where it is taken up by the elevators in the manner already described.

The apron 19 trims off the snow at the bottom and the sides of the cut and leaves it with sloping banks, which are not as liable to break down as they would be if they were of 90 other form. The space between the elevators is preferably open in front beneath the cutter, so that more or less of the snow may pass over the top of the apron, under the cutter, and into this space.

The cutter with the spiral knives is more expensive; but I consider this form preferable, as it will be more easily forced into the snow, and will therefore require much less power to drive the plow.

I claim as my invention—

1. The combination, in a snow-plow, of the

hollow conical cutter open at its rear end and formed of the series of knives 7, arranged with open spaces between them, and means for discharging the snow that passes to the interior and out of the rear end of said cutter, substantially as described.

2. The combination, in a snow-plow, of the hollow conical cutter open at its rear end and formed of the series of knives arranged with open spaces between them, means for rotating said cutter, and an elevator for raising and discharging the snow, arranged in the rear of said cutter, substantially as described.

15 3. The combination, in a snow-plow, of the hollow conical cutter open at its rear end

and formed of the series of knives 7, arranged with the open spaces between them, means for rotating said cutter, and the bottom and side aprons, 19, substantially as described. 20

4. The combination, in a snow-plow, of the hollow conical cutter open at its rear end and formed of the series of spiral knives 7, arranged with open spaces between them, and means for discharging the snow that passes 25 to the interior of said cutter, substantially as described.

EDWARD P. CALDWELL.
